GRILLE

Robert T. Bogan, Jr., 3620 High St., NE,
Albuquerque, N. Mex. 87107

Filed Oct. 17, 1968, Ser. No. 14,032

Term of patent 14 years

Int. Cl. D25—01

U.S. Cl. D13—1

FIG. 1

FIG. 3

FIG. 1 is a front elevation of a portion of a grille embodying my new design, a rear elevation thereof being the same in appearance but interposed in alternating relation with the front;

FIG. 2 is a vertical section, taken along line 2—2 of FIG. 1; and

FIG. 3 is a fragmentary horizontal section, taken along line 3—3 of FIG. 1.

I claim:

The ornamental design for a grille, as shown and described.
